FLOATING SAFE

Charles H. Balko, Boston, Pa., assignor of one-half to Mike Blaha, Versailles, Pa.

Application December 10, 1935, Serial No. 53,814

1 Claim. (Cl. 9—10)

This invention relates to receptacles and more particularly to a receptacle designed for use as a safe, which may be conveniently carried in airplanes or other moving vehicles.

5 An object of this invention is to provide a receptacle which embodies means whereby the receptacle may be sealed and locked and when in this condition may be placed in water upon which the receptacle will float.

10 Another object of this invention is to provide a safe or receptacle which is capable of floating on water and, at the same time, may act as a life preserver due to the unsinkable construction thereof.

15 A further object of this invention is to provide a floating safe of this character which is not only capable of floating on water but which embodies means whereby the safe or receptacle will not readily burn so that the safe or receptacle 20 may be carried in an airplane and articles sealed and locked therein against destruction by fire or loss through sinking in water.

25 A still further object of this invention is to provide in a device of this kind, means whereby a light may be attached to the device so that the position thereof in water or on land may be readily determined at night.

30 Still another object of this invention is to provide in a device of this kind means to facilitate removal of the safe or receptacle from the water, or the like, the device being provided with opposed handles which, in the event the device is used as a life preserver, may be grasped by a person in the water or may be used for the purpose 35 of attaching hooks or lines thereto in order to raise the device out of the water.

35 The above and various other objects and advantages of this invention will in part be described in, and in part be understood from the 40 following detail description of the present preferred embodiment, the same being illustrated in the accompanying drawing, wherein:—

45 Figure 1 is a longitudinal section partly in detail of a floating safe constructed according to an embodiment of this invention.

Figure 2 is a fragmentary sectional view taken on the line 2—2 of Figure 1.

50 Referring to the drawing wherein like symbols designate corresponding parts throughout the several views, the numeral 10 designates generally a receptacle which is closed at one end and provided with a neck 11 at one end thereof. The body 10, in the present instance, is preferably constructed of fibre or some suitable material 55 which may be either inherently fireproof or may

be made fireproof in any suitable manner and the body 10 is provided at its bottom 13 with a buoyant body 12 in the form of a relatively large section of cork or other relatively light material which is very buoyant and is capable of supporting 5 the bag or body 10 in water.

The body 10 is provided at a point adjacent the neck 11 with opposed handles 14 of suitable construction which are preferably so constructed that they will normally be disposed in outstanding relation to the body 10. When the device is placed 10 in water these handles 14 may serve as a means to which a rope or other line may be attached in order to raise the device out of the water or these handles may be grasped by a person in the water 15 so that the receptacle or safe 10 may be used as a life preserver when in water.

The neck 11 may be made of metal or relatively rigid material and is provided with threads 15 on the inside thereof so that a closure, generally 20 designated as 16, may be threadably secured in the neck 11. This closure 16 comprises a threaded inner portion or plug 17 and a cap or outer portion 18 having a diameter substantially larger than the diameter of the neck 11 so that, if desired, a gasket or like sealing means may be carried by the closure 16 and engage against the outer end of the neck 11. The neck 11, at a point below the top thereof, is provided with a pair of ears or spaced apart lugs 19 and a locking member 20 is pivotally secured between the ears 19. This locking member 20 includes a rod 21 having an enlargement or casing 22 at its free end which is adapted to engage an outstanding projection 23 carried by the cap 18. Preferably, the housing 30 or casing 22 is adapted to enclose a combination lock so that when the locking arm 21 is raised to a locking position, the cap 16 will be held against rotation. If desired, the position of the locking member 20 may be reversed, that is, the locking member 20 may be pivotally secured to the cap 40 16 and the casing 22 but disposed on the lower end of the arm 21 and engaged with a suitable projection secured to the neck 11.

In order to provide a means whereby, in the 45 event the safe hereinafter described is thrown into the water, the safe may be readily picked up at night, I have provided a casing 24 which is secured to the top of the cap 16 and is adapted to receive a plurality of battery cells. The casing 24 is provided with a socket 25 to receive a light casing 26 embodying a switch 27. This casing 26 is electrically connected to the batteries 28 which are disposed in the casing 24 and when the entire device is thrown into the water, the 55

switch 27 may be moved to closed position thereby energizing the light in the casing 26 and providing a means in the form of a signal by which the device may be readily found at night. If desired, the casing 24 may be of a readily detachable construction, being provided with clips at opposed points for engagement with the periphery of the cap portion 18. In this manner, the casing 24 may be normally left off of the cap 16 but if it is found necessary, as where the device is thrown into the water at night, the casing may be readily attached to the cap.

In the use of this device, the articles may be placed inside the body 10 and the cap 16 then threaded into the neck 11. When the cap 16 is in tight position, the enlargement 23 embodying a keeper for the lock carried by the casing 22 will be disposed in a position to receive the locking bolt carried by the housing 22. The arm 21

may then be swung to a substantially vertical position and the cap 16 then locked against turning.

I claim:—

A floating safe comprising a hollow body, buoyant means within the body in the lower portion thereof, a neck carried by the body provided with interior threads, a threaded cap engaging the neck, an outstanding arm fixed to the neck, a link pivoted at one end to said arm, a locking member carried by the opposite end of said arm, an outstanding keeper carried by said cap for engagement with said locking member to hold the cap against turning, a battery casing carried by the cap provided with a socket, a signal casing engageable in said socket and a light bulb in said signal casing.

CHARLES H. BALKO.
